Attorney

UNITED STATES PATENT OFFICE.

ANTHONY GIARDINO, OF BROCKTON, MASSACHUSETTS.

CLASP.

1,274,160.

Specification of Letters Patent. Patented July 30, 1918.

Application filed October 23, 1916. Serial No. 127,204.

To all whom it may concern:

Be it known that I, ANTHONY GIARDINO, a citizen of the United States, residing at Brockton, in the county of Plymouth and State of Massachusetts, have invented certain useful Improvements in Clasps, of which the following is a specification, reference being had therein to the accompanying drawing.

10 The invention relates to clasps, and more particularly to the class of tag clasps.

The primary object of the invention is the provision of a clasp of this character wherein a marking tag of any type can be firmly fastened therein so that the tag can be conveniently hung upon articles of merchandise for identification purposes.

Another object of the invention is the provision of a clasp of this character wherein the construction thereof is novel in form so as to allow free flexibility in the handling of the tag when inspecting the same and is attached for the marking of articles of merchandise so that there is no possibility of 20 the separation of the tag from the merchandise, yet the same can be readily inspected for identification purposes.

A further object of the invention is the provision of a clasp of this character wherein 30 the clip ends are of novel form so that the tag can be conveniently fastened and also the clasp engaged with the article of merchandise without accidental separation of the tag or clasp, the clips for the attachment of the clasp being readily operated for the opening and closing thereof to engage the tag or article of merchandise or for the removal of the clasp with despatch.

A further object of the invention is the provision of a clasp of this character which is simple in construction, thoroughly reliable and efficient in its purpose, neat, attractive, strong, durable and inexpensive in manufacture.

45 Other objects will be in part obvious and in part hereinafter described.

The invention accordingly consists in the features of construction, combination of elements and arrangement of parts which will be exemplified in the construction herein-after described, and the scope of the application of which will be indicated in the appended claim.

In the accompanying drawings:

Figure 1 is a plan view of my invention 55 of clasp;

Fig. 2 is a perspective view of one of the clips thereof;

Fig. 3 is a perspective view of the other clip; and

Fig. 4 is a vertical longitudinal sectional view through Fig. 1.

In Figs. 1 to 4 of the drawings there is illustrated the details of my invention, wherein the eye terminals of the resilient 65 limbs of the frames 21 and 22 have loosely connected thereto clips, one of which comprises the swinging jaws 23 formed with the pivot coils 24 in which is engaged a pivot 25 for swingingly connecting the jaws. The 70 free ends of these jaws are bent inwardly toward each other and are formed with pointed terminals 26 for biting into the tag body for the fastening of the same in the clip, the jaws being designed to work toward each other under the action of the tension of the frame 21.

The other clip comprises the swinging jaws 27 connected in a like manner to the jaws 23, and the lever ends 28 of these jaws 80 are formed respectively with a keeper 29 and a safety pin extension 30, the latter being engageable in the keeper 29 so as to hold the jaws 27 closed. On releasing the safety pin extension 29 and pressing inwardly upon the lever ends of said jaws 27 the same can be opened. These jaws 27 are formed with rounded hook terminals 35 which are adapted to engage with the ordinary loop of a shoe (not shown) for the 90 hanging of the clasp thereon, as will be apparent.

From the foregoing description, taken in connection with the accompanying drawings, the construction and operation of the 95 herein described clasp will be readily apparent and, therefore, a more extended explanation has been omitted.

Having thus described my invention, I claim:

A device of the class described consisting in combination, of a pair of wire members, each provided with an intermediate integral eye, the two wire members extending longitudinally of each other and being curved in 105 opposing directions on opposite sides of said

eyes, a pivot disposed at right angles to the plane of said members and passing through said eyes to pivotally connect them together, the outer portion of one of said members 5 being bent to provide a keeper arm extending across toward the other wire member which is provided with a forwardly curving

hook, the outer end of said keeper arm being provided with a right angularly disposed loop adapted to engage said hook so 10 as to separate said members at one end and bring them together at another end.

In testimony whereof I affix my signature.
ANTHONY GIARDINO.
